POSTAGE STAMPING MACHINE

Wilhelm Friedrichs, Berlin-Reinickendorf-Ost,
GermanyApplication November 4, 1932, Serial No. 641,282
In Germany October 3, 1927

9 Claims. (Cl. 101—91)

This invention relates to postage stamping machines and has for its object to provide a machine of this character wherein the setting mechanism is common to both the printing mechanism and the counting mechanism, being permanently disposed in operative relation to both mechanisms so as to prevent the fraudulent use of the postage stamping machine and also to obviate possibility of error occurring in the transfer of values set up in the printing mechanism to the counting mechanism.

A further object of the invention is the provision of a machine in which the simple operation of shifting a single setting member simultaneously adjusts a printing member and sets up a value corresponding to the adjustment of the printing member which value, upon initiation of operation of the printing mechanism, is carried into the counting mechanism.

The present application is a continuation in part of my application Serial No. 308,747, filed September 27, 1928, to which attention is invited.

In the accompanying drawings wherein an approved embodiment of the invention is illustrated:

Fig. 1 is a front elevation of the improved machine, the casing being removed.

Fig. 2 is a top plan view of the machine, casing and the counter-pressure roller device being removed.

Fig. 3 is a section on the line 3—3 of Fig. 1.

Fig. 4 is a section on the line 4—4 of Fig. 1.

Fig. 5 is a fragmentary plan view of the machine showing the casing in position.

Fig. 6 is a detail view of the main shaft showing two setting devices, one being in elevation and the other in section.

Referring to the drawings in detail, 10 indicates the base plate of a frame structure which also includes the end uprights 11 and the intermediate upright 12. The rotatable printing drum 13 is located in the space between the intermediate frame member and the end frame member 11 and the counting mechanism designated generally at 14 is located in the frame at the opposite side of the intermediate upright 12. The printing operation is effected by means of a main shaft 15 rotatably mounted in the uprights 11 and 12 and provided at its outer end with a hand crank 16.

The setting mechanism designated generally at 17 is mounted on the main shaft 15 and is constituted by a plurality of setting discs 18 all of which are confined between collars 19

rigidly secured to the shaft and coupled by rods 20 passing through the discs 18 and non-rotatably securing the latter on the main shaft. Teeth 21 are mounted for radial movement in guide slots provided in each setting disc 18 and these teeth are projected outwardly by a cam disc 22 having a cam-shaped slot therein receiving lateral projections on the teeth 21. The portion of the machine casing 23 which encloses the setting mechanism is formed with slots 24 shown in Fig. 5 through which the handles 25 of the cam discs 22 project and suitably arranged numerals ranging from 0 to 9 are arranged laterally of the slots 24 to aid in setting the handles 25 to the desired positions.

A setting gear 26 associated with the printing mechanism to be described in detail hereinafter is secured to each cam disc 22 and is turned therewith relatively to the setting disc 18 during adjustment of the handle 25. A spring 20 pressed pawl 27 is pivoted to each gear wheel 22 and cooperates with a toothed wheel 28 secured to the disc 18 whereby the cam disc and wheel 25 are yieldably retained in adjusted position against unintentional displacement.

Upon rotary movement of the main shaft 15 the entire setting mechanism moves therewith and the teeth 21 which have been moved to operative position mesh with pinions 30 and cause the latter to revolve. The pinions 30 are 30 in mesh with the gear wheels 31 of the several numeral wheels 32 rotatably mounted on a supporting shaft 33, the numeral wheels 32 having the numerals from 0 to 9 marked thereon and visible through windows 34 provided in the casing 23.

A gear wheel 35 keyed to the main shaft 15 serves as a driving gear for effecting rotary movement of the printing drum, as will hereinafter more fully appear and in addition operates the tens transfer mechanism. The latter mechanism includes a gear wheel 36 which meshes with the gear wheel 35 and is rotatable on a stud 37. A segmental gear 38 is secured at one side of the gear wheel 36 and a stop disc 39 having recesses 40 therein is secured at the other side of the segmental gear 38, the parts 36, 38, and 39 being secured together and moving as a unit in response to rotary movement of the gear wheel 35 and the main shaft 15.

The counting mechanism 14, as shown in Figs. 1 and 2, is mounted in a supplemental frame 41, the shaft 33 and the shaft 30a of the pinions 30 being journaled in the uprights of said supplemental frame. A transfer shaft 42 is also jour-

50

40

45

50

55

nalled in the frame 41 and an arm 43 is fixed to one end thereof. The outer extremity of the arm 43 is curved as at 44 in conformity with and normally engages the circumferential edge of the 5 stop disc 39 whereby the shaft 42 is normally held against rotation. A gear wheel 45 is secured to the shaft 42 laterally of the arm 43 and is adapted to mesh with the segmental gear 38 when the teeth thereof move into operative position with 10 respect to the gear wheel 45. Pairs of star wheels 46 and 47 are arranged between the shafts 33 and 42 and a pair of said wheels is associated with each numeral disc 32. Each star wheel is provided with three points or teeth and the teeth 15 of one star wheel of the pair are displaced with respect to those of the other wheel. The star wheel 46 normally occupies a position permitting free rotation of the gear wheel 31 as during the counting movement of the discs 32 but, upon being 20 turned a fraction of a revolution, one tooth thereof engages the adjacent gear wheel 31 and moves the latter the distance of one tooth thereof. The other star wheel 47 of this pair is arranged in the path of a radially projecting tooth 48 of the counting 25 disc 32 of the next lower denomination and a tooth of the latter star wheel 47, as the numeral disc 32 last mentioned passes from 9 to 0, is engaged by the tooth 48 and is turned through an angle sufficient to position another tooth of the 30 star wheel 47 in the path of a radial projection 49 on the shaft 42 and thus, when the shaft 42 is revolved, the movement of the projection 49 is transmitted to a tooth of the star wheel 47 and the latter acting on the star wheel 46, causes the latter 35 to advance the numeral disc 32 of the next higher denomination the distance of one tooth.

As will be understood, the value set up in the setting mechanism 17 is transferred to the 40 numeral discs 32 during the first half of the revolution of the main shaft 15 while during the second half of the revolution of said shaft the teeth of the segmental gear 38 which revolves with the gear wheel 36 are moved into mesh with the gear wheel 45 and the rotation of the projections 49 carried by the shaft 42 effects the operation of 45 the star wheels 46 and 47 through which the tens transfer is effected.

The printing drum 13 is provided with a hub 51 which is rotatably mounted in the intermediate 50 upright 12 and provided with a gear wheel 52 meshing with the gear wheel 35 whereby rotary movement is imparted to the printing drum 13 during rotation of the main shaft 15. The hub 51 is of hollow form and receives a plurality of 55 telescopic shafts 53 arranged one within the other and the innermost shaft of which is solid and journaled in a bearing 54 in one of the end uprights of the frame. The hollow telescopic shafts 53 terminate in stepped relation and carry gear 60 wheels 55 each of which meshes with the gear wheel 26 of one of the setting discs so that when the cam discs 22 are turned to adjust the teeth 21 the rotary movement of the discs 22 is transmitted to the shafts 53 through the gear wheels 26 and 55.

The several shafts 53 terminate within the hollow drum 13 in stepped relation and each carries 65 a gear wheel 56. Intermediate the shafts 53 and the rim of the drum 13 a shaft 57 is secured in the side walls of the latter and supports a plurality of 70 type wheels 58 corresponding in number to the number of setting discs 18 and the peripheral portions of the type wheels project through an aperture provided in the rim of the drum 13. The several type wheels 58 are arranged in spaced 75 relation and receive the gear wheels 56 there-

between, said gear wheels 56 meshing with gear wheels 59. As will be understood, one gear wheel 59 is secured to each type wheel 58 whereby the latter are adjusted during the rotary movement of the shafts 53 through the intermediary of the 5 gear wheels 56 and 59.

A locking pawl is pivotally mounted at 61 in the drum 13 and is provided with a plurality of teeth respectively engaging the several gear wheels 59. Within the drum, the multiple pawl 10 60 is connected with an arm 62 which latter is connected with a spring 63 normally retaining the teeth of the multiple pawl in engagement with the teeth of the several gear wheels 59 whereby the latter are prevented from accidental 15 or unauthorized displacement during the printing operation. Externally of the drum 13 the supporting shaft 61 of the multiple pawl is connected with an arm carrying a roller 64. A releasing lever 65 is pivoted at 66 on the inside 20 of the upright 11 and the upper end thereof is normally retained in engagement with the stop pin 67 carried by the upright 11 by the tension of a spring 68 connected at one end with the lower extremity of the releasing lever 65 and at 25 its opposite end to a pin 69 located on the inside of the upright 11. The upper extremity of the lever 65 is provided with a laterally projecting operating pin 70 which projects through a slot provided in the upright 11 to the exterior of the 30 machine and its casing whereby the releasing lever 65 may be actuated. The roller 64 is so disposed that when the drum 13 is in the position of rest, as shown in Fig. 4, said roller lies directly in the path of swinging movement of the 35 upper extremity of the lever 65 and thus, when the operating pin 70 is pressed forwardly, the multiple pawl 60 is swung on its pivot 61 and, 40 disengaging the gear wheels 59, permits the latter to freely turn as the cam discs 22 are operated in the act of setting up a value in the machine. However, following the setting up operation the lever 65 is released, and as the printing movement of the drum 13 is initiated as by the operation of the operating crank 16, the roller 64 45 moves out of the path of the lever 65 and the spring 63 automatically brings the multiple pawl 60 into locking engagement with the gear wheels 59, thereby positively locking the type wheels 58 against readjustment during the printing operation. 50

A casing 72 for the article feed device for the printing mechanism is arranged above the printing drum 13 and supports a shaft 73 on which a pair of angular levers 74 is pivotally mounted. One lever 74 carries a counter pressure roller 75 located immediately above the printing drum 13 and the other lever 74 carries a feed roller 76. Both levers 74 are normally urged downwardly by the tension of springs 77 and they may be lifted to an elevated position by means of a slide 78 which is mounted to move longitudinally on guide pins 79 secured in the casing 72 and is provided with inclined surfaces 80 engaging pins 81 fixed to the lever 74. Thus, when the slide 78 is moved rearwardly, the inclined surfaces 80 thereof coat with the pins 81 to shift the levers 74 and elevate the rollers 75 and 76 to inoperative position. A feed roller 82 is arranged below and cooperates with the roller 76 and is positively driven during the operation of the machine through an intermediate gear wheel 83 meshing with a gear wheel 84 fixed to the hub of the printing drum 13. 70

In the operation of the machine, the type 75

wheels 58 are set to a position to print a desired value by suitable adjustment of the setting arms 25, the movement of the setting discs 22 operating to simultaneously project a corresponding number of teeth 21 and to set the type wheels 60. The setting movement of the type wheels 60, as will be understood, is effected during turning movement of the cam discs 22 through the gear wheels 26 which revolve with the cam discs 22 and cause the gear wheels 55 and the associated shafts 53 to rotate also. The rotary movement of the shafts 53 and the gear wheels 56 connected therewith is transmitted to the type wheels 60 through the pinions 59. Preliminary to adjusting the type wheels, however, it is necessary to bring the drum 13 to its position of rest as shown in Fig. 4 and to tilt the lever 65 by displacing the operating pin 70 thereof forwardly. This displacement of the lever 65 causes the multiple pawl 60 to be swung outwardly thereby releasing the pinions 59 and permitting rotary adjustment of the pinions of the type wheels 58. Having set the printing mechanism to the desired value, the article to be postmarked is introduced between the rollers 76 and 82, and upon initiation of rotation of the main shaft 15, as by operation of the crank 16, the article is fed rearwardly by the rotary movement of the feed roller 82, and during the rotary movement of the printing drum 13, the postage value expressed by the adjustment of the type wheels 58 is impressed upon the article. Coincident with the printing operation, the projected teeth 22 of the several setting discs 18 actuate the respective pinions 30 associated with the related numeral wheels 32 and the latter are advanced. During the transfer of the value set up in the setting mechanism 17 to the numeral wheels 32, no rotary movement is imparted to the gear wheel 65, but during the second half of the revolution of the main shaft 15 the teeth of the segmental gear 38 enter into mesh with the gear wheel 45 and revolve the shaft 42, the arm 43 passing through one of the recesses 40 in the disc 39 during the initiation of the revolution of the shaft 42. If, during the transfer of a value from the setting mechanism to the counting mechanism 14 one of the counting discs 32 passes from 9 to 0, the tooth 48 of that numeral disc engages the star wheel 47 and displaces the latter to such position that during the rotary movement of the shaft 42 which succeeds the adjustment of the numeral wheel 32, the arm 49 engages the star wheel 47 which has been thus displaced from its normal position and, acting on one of the teeth of said star wheel, causes the latter to revolve together with its companion wheel 46 and the latter, cooperating with the gear wheel 31 of the numeral disc 32 of the next higher denomination, causes the last mentioned numeral wheel to advance.

From the foregoing it will be understood that the operation of setting a value in the setting mechanism 17 simultaneously and unalterably sets a corresponding value in the printing mechanism due to the fact that the gear wheels 26 directly mounted on the setting cams 22 are permanently coupled with the printing discs through the gear train 26, 55, 56, and 59. Having set the desired value, the crank 16 is operated and the printing drum 13 is set in operation by the intermeshing gear wheels 35 and 52, the gear wheels 26 revolving in a unit in their adjusted positions with the shaft 15 and the gear wheels

55 meshing and revolving with the gear wheels 26.

What I claim is:

1. In a machine of the character described, a setting mechanism, a rotary printing drum having printing members therein coupled with and adjustable by said setting mechanism, means for imparting rotary printing movement to said drum, said setting mechanism moving with said moving means during the printing movement of the drum and remaining coupled with said printing members during the printing operation, and means operative upon initiation of the printing movement of the drum to lock the printing members in adjusted position.

2. In a machine of the character described, a setting mechanism, a rotary printing drum having printing members therein coupled with and adjustable by said setting mechanism, means for imparting rotary printing movement to said drum, said setting mechanism moving with said moving means during the printing movement of the drum and remaining coupled with said printing members during the printing operation, means operative upon initiation of the printing movement of the drum to lock the printing members in adjusted position, and means operable only when the drum is in its position of rest to engage and release said locking means.

3. In a machine of the character described, a rotary printing drum including relatively adjustable printing members located therein, a setting mechanism including a plurality of setting members mounted to turn about a common axis removed from the axis of said drum and constantly connected with said printing members for setting the latter, and means for imparting rotary printing movement to said drum, the last mentioned means being disposed coaxially of said setting members.

4. In a machine of the character described, a rotary printing drum including relatively adjustable printing members located therein, a setting mechanism including a plurality of setting members mounted to turn about a common axis removed from the axis of said drum and constantly connected with said printing members for setting the latter, means for imparting rotary printing movement to said drum, and means carried by said drum to lock said printing members in adjusted position.

5. In a machine of the character described, a rotary printing drum including relatively adjustable printing members located therein, a setting mechanism including a plurality of setting members mounted to turn about a common axis removed from the axis of said drum and connected with said printing members for setting the latter, means for imparting rotary printing movement to said drum, means to lock said printing members in adjusted position and means mounted independently of said drum and engageable with said locking means when said drum is in a position of rest to move said locking means to inoperative position and permit adjustment of said printing members.

6. In a machine of the character described, a main shaft, a rotary printing drum axially displaced from said shaft and including a plurality of relatively adjustable printing members, a setting mechanism carried by the main shaft and including a plurality of independently adjustable setting members, means constantly connecting each of said setting members with one of said printing members whereby the printing members and setting members are simultaneously adjusted,

and means for imparting rotary movement of the main shaft to the printing drum.

7. In a machine of the character described, a main shaft, a rotary printing drum axially displaced from said shaft and including a plurality of relatively adjustable printing members, a setting mechanism carried by the main shaft and including a plurality of independently adjustable setting members, means constantly connecting each of said setting members with one of said printing members, and means for imparting rotary movement of the main shaft to the printing drum, said means connecting the setting members with the printing members including a plurality of telescopic shafts arranged concentrically of the printing drum.

8. In a machine of the character described, a setting mechanism, a rotary printing drum having printing members therein coupled with and adjustable by said setting mechanism, means for rotating the drum to printing position, said setting mechanism moving with said moving means

during the printing movement of the drum and remaining coupled with said printing members during the printing operation, locking means for the printing wheels normally effective, and lock releasing means ineffective when the drum is out of printing position. 5

9. In a machine of the character described, a printing drum rotatable about a fixed axis, a plurality of printing members mounted in said drum and relatively adjustable to different set positions, a shaft rotatable about a fixed axis removed from the axis of said drum, a plurality of setting members mounted on said shaft for rotation to different positions and constantly connected with said printing members to set the 10 latter, means to impart rotary movement to said drum including operating connections between said drum and said shaft, and means carried by said drum to lock said printing members in set 15 positions. 20

WILHELM FRIEDRICHs.
